UNITED STATES PATENT OFFICE

SAMUEL KRAMER, OF NEW YORK, N. Y.

DESIGN FOR A FLOOR LAMP

Application filed November 16, 1929. Serial No. 33,472. Term of patent 8½ years.

To all whom it may concern:

Be it known that I, SAMUEL KRAMER, a citizen of the United States, and resident of New York city, in the county of Kings, New York, have invented a certain new, original, and ornamental Design for a Floor Lamp, of which the following is a specification, reference being had to the accompanying drawing, forming part thereof.

The figure of the drawing is a front view of a floor lamp showing my new design.

I claim:

The ornamental design for a floor lamp substantially as shown.

SAMUEL KRAMER.
